WELL PUMPING APPARATUS

Eugene J. Weatherby, Bartlesville, Okla., assignor
to Phillips Petroleum Company, a corporation
of Delaware

Application March 17, 1941, Serial No. 383,839

3 Claims. (Cl. 103—46)

This invention relates to an apparatus for pumping wells, including deep hydrocarbon wells. This invention is especially adapted to the pumping of such wells by an apparatus wherein the energy developed by a rotating prime mover is converted into reciprocating energy for actuating a reciprocating pump through the coaction of hydraulic means to thereby minimize shock loads and prolong the useful life of the pumping equipment.

Two general classes of pumping equipment are principally used in pumping fluids from underground reservoirs. These pumps are classified as the centrifugal and reciprocating types. Centrifugal pumps are directly connected to the prime mover by means of a rotatable drive shaft. During the past few years, certain reciprocating pumps have been devised to operate by means of a high pressure fluid which is conveyed to the pump from the surface of the ground. This type of pump has certain advantages over the common type of reciprocating well pump which is actuated by means of a string of sucker rods from the surface of the ground. All of the aforementioned types of subsurface pumps, however, have a certain degree of inflexibility in operation, since the transmission of power from the prime mover to the pump is direct and positive. Hence, excessive loading of the pump or shock loads, caused by changes in the direction of motion of moving parts of the pumping equipment, must be absorbed by the prime mover or the auxiliary equipment. These conditions are especially noticeable in sucker rod actuated reciprocating pumps, where breakage of the sucker rods is a major cause of repair to the pumping equipment.

By the practice of my instant invention, I am able to operate any type of down-hole equipment which has moving parts subject to external loading without causing excessive loading of any of said moving parts. Further, I am able to transmit power for pumping fluids from underground reservoirs regardless of the depth from which the fluid must be raised, and by the application of my invention to a reciprocating pump, I can provide a positive displacement pump for lifting fluids from great depths without the employment of expensive equipment, such as sucker rods, rig fronts, counterbalance weights and the like.

It is therefore the primary object of this invention to minimize shock loads in well pumping equipment.

Another object of this invention is to provide

apparatus of the character indicated which is adapted to economically and effectively pump wells, including hydrocarbon oil wells.

These and additional objects and advantages 5 will be apparent to persons skilled in the art by reference to the following description and annexed drawing, which is an elevation view of a preferred embodiment of my invention.

Referring to the drawing I have denoted there- 10 in a well bore 1 which extends downwardly from the surface of the ground (not shown). A string of flow tubing 2 is suspended within the well bore and serves the dual purpose of supporting a conventional type of reciprocating pump, generally indicated by reference numeral 3, at its lower end and of conveying well fluid from the pump upwardly to the surface of the ground. Secured to the lower portion of the pump is a gear train assembly 4 which is operatively connected to the pump and to a rotatable shaft 5 to convert the rotational motion of this shaft into reciprocating motion in the pump. Shaft 5 is also connected to a fluid drive, such as a hydraulic coupling or clutch 6, which in turn is connected by a second rotatable shaft 7 to a prime mover 8, such as the electric motor designated in the drawing. A conductor cable 9 transmits electrical energy to the motor from a suitable source of electricity at the surface of the ground. While an electric motor is recommended in the practice of my invention, it is to be understood that any type of prime mover which will operate satisfactorily to perform its intended function in a well bore may be used.

35 In operation, the electrical energy that is transmitted to motor 8, by means of cable 9, is converted by the motor into mechanical energy to thereby rotate shaft 7. The rotational motion of shaft 7 is in turn transmitted through hydraulic coupling or clutch 6 to shaft 5. Through the coaction of gear train 4, rotation of shaft 5 is transformed into reciprocating motion of the usual piston within positive displacement pump 3. The gear train also functions as a speed reducer between the electric motor and the pump. Fluid in the well bore is admitted into the pump and is urged upwardly through flow string 2 to the surface of the ground. If the pump lifts a uniform load at all times, its number of strokes per unit time will be substantially constant. On the other hand, if the load on the pump varies, the operating speed of the pump will not be uniform, as the hydraulic coupling allows a certain amount of "slip" when a load, which is greater than the usual load, is placed on the

pump. This causes shaft 5 to slow down, and causes the reciprocating pump to operate more slowly. Thus, the "slip" in the hydraulic coupling relieves the pump and gear assembly of any excessive stresses and prevents overloading of the prime mover.

From the foregoing, it is believed that the apparatus for practicing my instant invention will be readily comprehended by persons skilled in the art. It is to be clearly understood, however, that various changes in the apparatus herewith shown and described may be resorted to without departing from the spirit of the invention as defined by the appended claims.

I claim:

1. An apparatus for pumping wells, the combination comprising a rotary prime mover disposed in a well bore, a fluid pump including a piston reciprocable therein in the well bore, and means for converting rotational motion in the prime mover into reciprocating motion of the piston, said means including a fluid coupling wherein shock loads in the apparatus during pumping operations are effectively minimized.

2. In apparatus for pumping wells, the combination comprising a rotary prime mover disposed in a well bore, a fluid pump including a piston reciprocable therein in the well bore, and means intermediate the prime mover and the pump for converting rotational motion in the prime mover into reciprocating motion of the piston, said means including a gear train and a fluid coupling wherein shock loads in the apparatus during pumping operations are effectively minimized.

3. In apparatus for pumping wells, the combination comprising an electric motor and a pump including a piston reciprocable therein disposed in spaced relationship in a well bore, means between the electric motor and the pump for converting rotational motion in the motor into reciprocating motion of the piston, said means including a gear train and a fluid coupling, the latter minimizing shock loads in the apparatus during pumping operations.

EUGENE J. WEATHERBY.
